W. B. GOULD, OF BOSTON, AND W. H. HARRIS, OF TAUNTON, MASSACHUSETTS.

Letters Patent No. 81,890, dated September 8, 1868.

IMPROVED ANTI-SLIPPING PLATE.

The Schedule referred to in these Letters Patent and making part of the same.

TO ALL WHOM IT MAY CONCERN:

Be it known that we, W. B. GOULD, of Boston, Suffolk county, and W. H. HARRIS, of Taunton, Bristol county, all in the State of Massachusetts, have invented an Improved Anti-Slipping Dish or Plate; and we do hereby declare that the following, taken in connection with the drawings which accompany and form part of this specification, is a description of our invention sufficient to enable those skilled in the art to practise it.

Our invention relates to the construction of an eating-dish or plate, designed particularly for the use of children, with reference to a provision for securing the same to a table, so that it cannot easily slip or be easily knocked off therefrom; and our improvement consists in a plate, having combined with and forming part of it a finger or clamp-piece, which lies parallel to the bottom of the plate, at a distance therefrom equal to or a little exceeding the ordinary thickness of a table, so that when the plate is placed upon the table, the finger extends beneath it, the finger being preferably provided with a clamp-screw, for fastening the plate.

The drawings represent, at A and B respectively, a plan and a cross-section of a plate embodying our improvement.

a denotes the plate or dish, preferably made of metal, and either square or rectangular in form, or round, or elliptic, as may be desirable.

The dish may be divided into two or more parts by suitable partitions, b.

To the bottom or under surface of the plate we solder or otherwise fasten one end of a long bar, c, bending the bar, so that the other end (and the greater part of the bar) extends under and parallel to the plate, as seen at B, this bar thus forming a finger to slide under a table when the plate slides upon the same, as seen at B, this finger having sufficient length, and lying near enough to the bottom surface of the plate, to hold the plate upon the table, though we prefer to use the clamp-screw d for the better securement of the plate, as indicated at A.

The plate being thus fastened to the table, it will be readily seen that it cannot easily be dislodged therefrom, except by turning back the clamp-screw.

For children and feeble-minded persons the device is very desirable, in preventing waste of food and breaking of dishes; and at sea, and in other places where there is continual movement or jarring of a table, the invention will be found to be particularly useful.

We claim a plate, provided with a device for securing it to a table, substantially as set forth.

W. B. GOULD,
W. H. HARRIS.
